UNITED STATES PATENT OFFICE.

ADOLPH H. F. SCHALAR, OF SAN FRANCISCO, CALIFORNIA, ASSIGNOR TO UNITED STATES WIRELESS PRINTING TELEGRAPH COMPANY, OF LOS ANGELES, CALIFORNIA, A CORPORATION OF WASHINGTON.

KEYBOARD.

No. 894,167.

Specification of Letters Patent.

Patented July 21, 1908.

Application filed July 13, 1908. Serial No. 326,063.

To all whom it may concern:

Be it known that I, ADOLPH H. F. SCHALAR, a citizen of the United States, residing at San Francisco, in the county of San Francisco and State of California, have invented certain new and useful Improvements in Keyboards, of which the following is a specification.

In transmitting intelligence by electrical impulses, as by metallic or wireless telegraphy, it is desirable that the impulses be caused to make a visible record, preferably by means of printed characters. In accomplishing this it is necessary that each transmitting station be provided with a keyboard for sending, and the receiving station or stations with means for receiving and recording messages.

The present invention relates to the keyboard of a transmitting instrument which is adapted to be connected with a receiving instrument containing a recording device; so that when anyone of the characters of the key-board is actuated, as by depressing a key-lever, the corresponding character at the receiver will be imprinted, as upon a tape. The transmitting instrument may also be provided with recording devices for keeping copies of messages sent. The key-levers are so arranged that when any one of them is depressed an electrical circuit will be closed and the lever will be locked until it is automatically released by the depression of a succeeding key-lever.

The apparatus is simple and portable and may be provided with a suitable case or cover.

The accompanying drawings illustrate an embodiment of the invention.

Figure 1, is a broken top plan of the keyboard; Fig. 2, is a side elevation of the same in its case; Fig. 3, is a similar view without the case; Figs. 4 and 5, are sectional views showing the key-levers in two positions; Fig. 6, is a broken detail view of the locking hinge; Fig. 7, is a detail view of the contact point at the end of the key-levers; Fig. 8, is a broken detail of the conductor bar.

In these drawings 1 indicates the base which may be of any desired size and material. Pivotaly mounted thereon, preferably by means of rods 2, are key-levers 3, the

forward end of each of which is provided with a key 4 which preferably bears the character which it is desired to reproduce by the electrical impulse. The rods 2 are preferably seated in notches 5 in side pieces 6 upon the base, and the levers are properly spaced apart upon the rods in any suitable manner, preferably by ears 7. The free end of each lever is formed into, or provided with an extension 8, which carries a contact point 9 insulated therefrom by a suitable bushing 10. The point 9 is connected with a transmission wire 11 through a binding post 12 and wire 13, and is adapted to be raised into engagement with the free end of one of a series of metallic fingers or contact points 14. The fingers are preferably flexible, and are all connected with a metallic bar 15 which is supported at its ends by ears on the side pieces 6, but insulated therefrom by the bushing 16. A wire 17 from any suitable source of electricity, not shown, is connected with the end of the bar 15, and thereby provides the fingers with current when the circuit is closed through any one of them.

The free end of each lever, preferably below the extension 8, is inclined as shown at 18, so that it is adapted to engage with a lip 19 on a flat bar or plate 20 which I term the locking hinge, and which is pivotally mounted on point screws 21. These screws extend through ears 22 on the base, and each end of the locking hinge is preferably extended and curved to form a socket 23, within which is seated a plug 24. This plug is provided with a hole in its end which forms a bearing for the pointed end of the screw 21. The lower edge of the plate 20 is also preferably flanged as shown at 25 to secure the proper rigidity. When a key is depressed the inclined portion of the free end of its lever engages with the lip 19, and thereby rocks the hinge 20 back against the tension of a spring 26; but as soon as the lever has passed above the lip 19, the spring instantly rocks the hinge and throws the lip under the end of the lever, holding its free end elevated while its forward end is depressed. As soon as another key is depressed the free end 18 of its lever rocks the hinge and throws the lip 19 from beneath the preceding key-lever, which is instantly returned to its normal position by a spring 27

attached to an elbow 28 under the frame 1; the last lever referred to being locked in its elevated position by the return movement of the hinge as was the other one. The lip 19 is 5 preferably beveled as shown at 29 to permit the locked key to start downwardly as soon as the hinge has been rocked to a very slight extent by the last key. The end 18 of each key-lever is preferably slightly rounded upon 10 its under side to assist in this movement. The rear end of each key-lever fits loosely in a notch 31 in a wall 30 on the base, and its forward end is adapted to strike a buffer 32 in order to limit its downward movement when 15 depressed, without jar.

The spacing on the distant machine is accomplished by a space-bar 33 on the transmitting key-board, which closes a circuit for that purpose the same as the other keys. 20 The space-bar 33 is pivoted at the forward ends of the side pieces 6 as shown at 33', and its free ends are inclined in the same manner as the free ends 18 of the key-levers 3, so that when the bar is depressed the hinge 20 will be 25 rocked and the last key released and its circuit broken. This bar has one contact like those of the key-levers, which is not shown.

A case or cover is preferably provided for the machine, the rear portion 34 of which extends over the free ends of the levers and the contact points, and is permanently secured to the base by screws 35. The forward portion 36 is hinged to the rear portion as shown at 37, so that it can be swung up out of the 35 way in order to give access to the keys. The swinging portion is provided with a handle 38, by means of which the entire apparatus can be easily carried.

At 40 is shown a stop key-lever which has 40 no contact on its free end. Its purpose is to throw back the locking hinge 20 in order to permit the last key-lever actuated to return to its normal position. The effect of the action just described is to stop any receiving 45 mechanism connected with the key-board; because, as the stop key-lever has no contact, and as the last key-lever actuated has returned to normal position and broken the circuit, no impulse is transmitted to the receiver.

It will be seen from the above description 50 that the key-board is very simple and compact, and that the different parts are so constructed and arranged that the electrical impulse for any desired character can be quickly transmitted by depressing the proper key. The locking hinge 20 holds the successive keys depressed, and the stop key-lever 40 releases the last key to clear the machine. The 60 cover can be placed over the keys temporarily for protection, or more permanently for transportation, thereby making a convenient structure in either case.

I do not limit myself to the precise and 65 literal construction herein described and

shown in the drawing, as I desire to avail myself of such modifications and equivalents as fall properly within the spirit of my invention.

What I claim is:—

1. In a keyboard, a plurality of pivoted transmitting key-levers each having a contact point at one end, a bar provided with a plurality of contact points, one for each of the said levers, and means for closing an electrical circuit through either of said points when its key-lever is actuated, and means for locking said levers when said circuits are so closed. 70

2. In a key board, a plurality of pivoted levers each provided with a key at one end and an extension at the other, a contact point in each extension, a bar, a plurality of flexible contact points extending therefrom in position to be engaged by the contact points of the levers; said points and bar being adapted to form parts of an electrical circuit, and means for locking said levers when said circuits are closed. 75

3. In a keyboard, a base, a plurality of key-levers pivotally mounted thereon each provided with a key at one end and an extension at the other, an insulated contact point in each extension, a binding post connected with each point, an insulated bar mounted on the base above the levers and provided with a plurality of flexible contact points one for each point in said extensions, and means for locking said levers with said points in contact. 90

4. In a keyboard, a base provided with a notched wall and with a plurality of bearings, a plurality of levers pivotally mounted in said bearings and having their rear portions within said notches, a key on the forward end of each lever and an insulated contact point on the rear end of each lever, a binding post connected with each point, an insulated bar above said levers and secured upon the base, a plurality of flexible contact 105 points extending from the bar in position to be engaged by the contact points of the levers, means for locking the levers with said points in contact, and means for connecting a source of electricity with one end of said bar. 110

5. In a key board, a perforated base provided with a notched wall and a plurality of ears or bearings, a plurality of elbows upon the under side of the base one for each perforation, a plurality of levers pivotally mounted with their rear portions within said notches, a key on the forward end of each lever and an insulated contact point on the rear end, a binding post connected with each point, a locking hinge pivotally mounted at 120 its ends, a spring for causing the hinge to engage with said levers when their rear ends are elevated, a spring extending from each lever through one of said perforations to one of the elbows for returning the lever to its 125 130

normal position when it is released from the locking hinge, and an insulated metallic bar provided with means for connection with a source of electricity, said bar being also provided with a plurality of contact points each adapted to be engaged by the contact point of one of the key-levers.

In testimony whereof, I have hereunto set my hand at Los Angeles California this 13th day of June 1906.

ADOLPH H. F. SCHAAAR.

In presence of—

L. W. SEELY,
ALFRED COOPER.
